Roots Sustainable Agricultural Technologies Ltd to start selling heat exchange probes in California <https://www.proactiveinvestors.co.uk/companies/news/928924/roots-sustainable-agricultural-technologies-to-start-selling-heat-exchange-probes-in-california-928924.html> Sep. 14, 2020 (Year: 2020).*

Primary Examiner — Leanne Was-Englehart

(74) **Attorney, Agent, or Firm:** — Vorys, Sater, Seymour and Pease LLP; William L. Klima

(57) **CLAIM**

The ornamental design for a device for temperature control in root zone, as shown and described.

DESCRIPTION

FIG. 1 is a right side perspective view of a device for temperature control in root zone;

FIG. 2 is a top perspective view thereof;

FIG. 3 is a bottom left side perspective view thereof;

FIG. 4 is a front perspective view thereof;

FIG. 5 is a front view thereof; rear view being a mirror image of FIG. 5;

FIG. 6 is a left side view thereof; right side view being identical to FIG. 6;

FIG. 7 is a top view thereof;

FIG. 8 is a bottom view thereof; and,

FIG. 9 is a bottom perspective view thereof.

The broken lines depict portions of the device for temperature control in root zone that form no part of the claimed design.

1 Claim, 9 Drawing Sheets
